UNITED STATES PATENT OFFICE

FREDERICK C. GLADECK, OF BROOKLYN, NEW YORK, ASSIGNOR TO INTERNATIONAL CIGAR MACHINERY COMPANY, A CORPORATION OF NEW JERSEY

LOCK-JOINT FOLDING ATTACHMENT FOR CIGAR ENVELOPING MACHINES

Application filed June 18, 1929. Serial No. 372,026.

This invention relates to lock joint cigar or other article enveloping machines designed to make a lock joint fold during the enveloping of cigars, sticks of candy, or similarly elongated articles in a suitable envelop or foil or other wrapping material.

The superiority of the lock joint fold, wherein one edge is folded over and behind and under the other edge, over the usual lap fold in which one edge of the wrapping material is merely laid on top of the other edge, is obvious since the former fold will keep air out and moisture in, and does not easily become undone. This fold is particularly advantageous for articles tapered towards the end, such as cigars, since this shape tends to cause the lap joint to gap open in the middle, defeating the purpose of the wrapping and making same less attractive in appearance.

In order that envelops so folded may not add appreciably to the cost of the enveloped cigar, it is important that a machine for this purpose be provided which will be quite rapid in operation, and which will perform the lock folding during the other enveloping operations. It is the main object of this invention to produce such a device. Still another object is to produce a device of this character requiring relatively few folding stations, simple in construction and requiring little change over prior lap fold enveloping machines.

With these and other objects not specifically mentioned in view, the invention consists in certain constructions and combinations which will be hereinafter fully described and then more particularly pointed out in the appended claims.

In the accompanying drawings which form a part of this specification and in which like characters of reference indicate the same or like parts:

Fig. 1 is a side elevation of a cigar enveloping machine embodying the invention;

Figs. 2 to 7 are detail views in side elevation, and partly in section, showing various steps in the operation of the mechanism shown in Fig. 1;

Fig. 8 is a detail side elevation of a part of the device shown in Fig. 1;

Fig. 9 is a front elevation of the detail shown in Fig. 8;

Fig. 10 is a detail side elevation of certain folding mechanism shown in Fig. 1; and

Fig. 11 is a rear elevation of the structure shown in Fig. 10.

In carrying the invention into effect there is provided means for forwarding cigars or other articles and envelops therefor having outstanding edges, means for pinching together the outstanding edges of the envelop over the cigar, mechanism for successively folding the leading edges over and tucking them behind trailing edges, and a device for laying the folded and tucked edges flat on the cigar to thereby produce a lock joint between the edges of the envelop. In the best constructions, said mechanism includes means for holding the outstanding edges of the envelop together, means for folding one of said edges over the other, and means for tucking the folded edge down behind the other. Preferably said mechanism includes an edge holding member and an edge folding member carried thereby. The above mentioned parts and means may be widely varied in construction within the scope of the claims, for the particular structure selected to illustrate the invention is but one of many possible concrete embodiments of the same. The invention, therefore, is not to be restricted to the precise details of the structure shown and described.

Referring to Fig. 1 of the drawings, the cigars or other articles to be enveloped are fed by any suitable means, such as a swinging transfer arm 21 and cooperating curved guide 22, into the pockets of turret arms 23. This turret and transfer mechanism is similar to that shown in a copending application for a cigar enveloping machine by Henry H. Wheeler, S. N. 203,082, filed July 2, 1927. In the aforesaid machine, lap folding and end folding mechanisms for folding the envelop about the cigars in the turret are disposed about its periphery. To adapt this enveloping machine to lock folding, the lap folding mechanism is omitted and the lock folding mechanism, as hereinafter described, is substituted in lieu thereof, retaining the end

folding mechanism. Accordingly, only so much of this enveloping machine structure is illustrated and described as is necessary to show the construction and operation of the lock folding mechanism and its cooperation with the turret and transfer mechanism of the enveloping machine. In the embodiment shown, the Geneva gear and operating mechanism for the turret is designed to stop the turret at six stations, at five of which the several enveloping and folding operations take place, which stations for convenience have been designated in the drawings and description by Roman numerals I to V, at station I of which the cigar is transferred to the turret and at station V of which the cigar is ejected therefrom. The turret 23, which is similar to that used in lap fold enveloping machines, is given intermittent and clockwise rotation by suitable means such as the Geneva gear 24 mounted on sleeve 25 surrounding a stationary horizontal turret shaft 26. Each of the fixed arms 23 of the turret carry a stationary jaw 27, and a movable forked lever 29 pivoted to the arm 23 at 28, which lever carries a relatively movable jaw 30. Each of the levers 29 is provided with two arms 31 and 32 extending rearwardly from the pivot point, one on each side of the arm 23. Rollers 33 on the arms 31 bear on the circumference of a cam 34 on the stationary shaft 26, arms 31 being thus held by springs 35.

The cigar C is pushed by the transfer arm 21 into the envelop F, which in the form selected for illustration is of foil, thereby partially enwrapping the cigar within the envelop. The arm thereafter pushes the cigar and envelop against a plunger 36 in a pocket formed by the jaws 27 and 30 against the outward pressure of spring 37 so that, as shown in Fig. 1, the cigar and envelop therefor are supported with their edges outstanding. The relative position of the cigar and the envelop material fed by the rollers 38 is made such that the portion of the envelop above the cigar is somewhat longer than that below the cigar to provide the extra material at the leading edge of the envelop for making the lock fold. As this occurs the wrapping material forming the envelop F, which is intermittently fed in timed relation to the movement of the transfer arm and the turret by feeding rollers 38, is cut off by the usual knife bar 39 and ledger block 40, the knife bar being oscillated in proper timed relation to the feeding movement of the envelop material.

In the preferred form of the device, the outstanding edges of the envelop are initially pinched together (station II, Fig. 1) by the intergeared pinchers 41 and 42, shown more in detail in Figs. 8 and 9. These pinchers are mounted just beyond the periphery of the turret and each has an envelop engaging surface extending the full width of the en-

velop, the surface of the pincher 42 being broader than that of the pincher 41 to correspond to the greater width of the leading outstanding edge of the envelop. These pinchers 41 and 42 are secured on shafts 43 and 44 respectively, suitably supported from the main frame of the enveloping machine, and these shafts carry gears 45 in mesh with each other whereby the pinchers are intergeared. The shaft 44 carries a lever 46 to which is connected by a pin 47, a rod 48 operated by suitable means not shown, such as a cam on one of the operating shafts of the enveloping machine for reciprocating said rod as indicated by the arrow in Fig. 1.

Mechanism is provided for holding the outstanding edges of the envelop together, at station III. These edge holding means, shown more in detail in Fig. 4, have envelop engaging surfaces similar to those of pinchers 41 and 42, but are independently actuated as follows: The holders 49 and 50 are each mounted on the shaft 51, the holder 49, being loose thereon, and the holder 50 secured thereto. The edge holder 49 has an arm 52 to which is connected by a pin 53 an operating rod 54, which is suitably reciprocated by means not shown from a shaft of the enveloping machine proper. The shaft 51 mounts an arm 55 to which is connected at 56 a rod 57, also suitably reciprocated by a cam not shown on a shaft of the enveloping machine. While it is preferred to provide means for initially pinching together the edges of the envelop at station II, it is apparent that in some instances this first pinching operation could well be dispensed with and such omission is contemplated, the edge holding means 49 serving for this purpose.

To fold the leading edge over and tuck it behind the trailing edge, holder 50 is provided with a folding plunger 58, and the arm 55 on the shaft 51 is provided with a tucking plunger 59. Each of these plungers is slidable in slots in said edge holder and arm. The folding plunger 58 is positioned with its forward end surface in alignment with and adjacent the edge surface of the element 50 and is movable against the portion of the leading edge of the envelop projecting above the trailing edge thereof. The tucking plunger 59 (Fig. 4) moves in a direction at right angles to the direction of movement of the folding plunger, being positioned with its working surface in alignment with the edge holding surface of the element 49.

The plunger 58 is actuated by the cam 61 mounted on a shaft 62, and the plunger 59 is controlled by the cam 63 on shaft 64, both shafts being supported by a frame of the enveloping machine to which the device embodying the invention is attached, and are connected with the drive shaft of the latter. At either side of the working face of the plunger 58 are mounted pins 65 to which are

secured springs 66 hooked to pins 67, which pull the slide outward into engagement with the operating surface of the cam 61. Similarly springs 69 secured to pins 68 in a slide 59 and anchored to pins 70 in the extension 60 of the plunger frame hold the rear end slide 59 in engagement with the cam 63, as shown in Fig. 10.

The folded and tucked edges are then laid flat by a stationary surface extending between station III and station V provided by the guide plate 71 and curved concentrically with the turret and mounted close to its periphery. This guide plate holds the foil wrapper in place while its ends are folded by the end folding mechanism of the above mentioned enveloping machine.

The operation of the devices above described is as follows: At station I (Fig. 2) a cigar C pushes the envelop F against the plunger 36, while at the same time the envelop is cut to length by knife 39. Further movement of the transfer plunger 21 pushes the cigar into the turret pocket between jaws 27 and 30 and folds the envelop around three sides of the cigar. As the turret moves from station I to station II, the depressed portion of the cam 34' permits the jaw 30 to close on the cigar and thus securely support the same and its envelop for folding. At station II, the outstanding edges of the envelop are pinched together by the pinchers 41 and 42, as shown in Fig. 3, which thereafter open as shown in dotted lines to permit movement of the turret arm to station III. At this station the outstanding edges of the envelop are again pinched together as shown in Fig. 4, and while so pinched together the plunger 58 folds the wider edge over the shorter trailing edge, as shown in Fig. 5, the top edge of the pinching face of the element 49 serving as a cooperating folding surface. The plunger 58 is then withdrawn, the pincher element 49 is opened by downward movement of the rod 54, and the plunger 59 moves downwardly as shown in Fig. 6, thereby tucking the overhang of the folded leading edge down behind the narrower trailing edge. The plunger 59 is thereafter moved up by the operation of the springs 69 and cam 63. Downward movement of the rod 57 and resulting movement of the pincher element 50 permits movement of the turret along the surface of the concentric guide 71 which lays the folded and tucked edges of the envelop flat, holding the same in this position during end folding at station IV, as shown in Fig. 7. At station V the jaw 30 is opened by raised portion 34'' of cam 34 acting on the lever 31, thereby ejecting the completely enveloped cigar.

What is claimed is:

1. The combination with means for supporting a cigar and envelop therefor having outstanding edges, of means for pinching together the outstanding edges of the envelop

over the cigar, mechanism for folding one edge over and tucking it behind the other, and a device for laying the folded and tucked edges flat on the cigar.

2. The combination with means for forwarding cigars and envelops therefor having outstanding edges, of means for successively pinching together outstanding edges of the envelops over the cigars, mechanism for successively folding the leading edges over and tucking them behind the trailing edges, and a device for laying the folded and tucked edges flat on the cigars.

3. The combination with means for forwarding cigars and envelops therefor having outstanding edges, of means for successively pinching together outstanding edges of the envelops over the cigars, mechanism for successively folding the leading edges over and tucking them behind the trailing edges, and a device for laying the folded and tucked edges flat on the cigars, said means, said mechanism, and said device being operative at separated positions in the travel of the forwarding means.

4. The combination with means for forwarding cigars and envelops therefor having outstanding edges, of means for successively pinching together outstanding edges of the envelops over the cigars, mechanism for successively folding the leading edges over and tucking them behind the trailing edges, and a device for laying the folded and tucked edges flat on the cigars, said means including intergeared pinchers operating to engage said outstanding edges and bring them together while closing.

5. The combination with means for forwarding cigars and envelops therefor having outstanding edges, of means for successively pinching together outstanding edges of the envelops over the cigars, mechanism for successively folding the leading edges over and tucking them behind the trailing edges, and a device for laying the folded and tucked edges flat on the cigars, said mechanism including means for holding the outstanding edges of an envelop together, means for folding one of said edges over the other, and means for tucking the folded edge down behind the other.

6. The combination with means for forwarding cigars and envelops therefor having outstanding edges, of means for successively pinching together outstanding edges of the envelops over the cigars, mechanism for successively folding the leading edges over and tucking them behind the trailing edges, and a device for laying the folded and tucked edges flat on the cigars, said mechanism including means for holding the outstanding edges of an envelop together, and independently actuated means for folding one of said edges over the other and means for then tucking the folded edge down behind the other.

7. The combination with means for forwarding cigars and envelops therefor having outstanding edges, of means for successively pinching together outstanding edges of the envelops over the cigars, mechanism for successively folding the leading edges over and tucking them behind the trailing edges, and a device for laying the folded and tucked edges flat on the cigars, said mechanism including independently actuated edge holding members.

8. The combination with means for forwarding cigars and envelops therefor having outstanding edges, of means for successively pinching together outstanding edges of the envelops over the cigars, mechanism for successively folding the leading edges over and tucking them behind the trailing edges, and a device for laying the folded and tucked edges flat on the cigars, said mechanism including an edge holding member, and an edge folding member carried thereby.

9. The combination with means for forwarding cigars and envelops therefor having outstanding edges, of means for successively pinching together outstanding edges of the envelops over the cigars, mechanism for successively folding the leading edges over and tucking them behind the trailing edges, and a device for laying the folded and tucked edges flat on the cigars, said mechanism including a cam-actuated folding plunger.

10. The combination with means for forwarding cigars and envelops therefor having outstanding edges, of means for successively pinching together outstanding edges of the envelops over the cigars, mechanism for successively folding the leading edges over and tucking them behind the trailing edges, and a device for laying the folded and tucked edges flat on the cigars, said mechanism including a cam-actuated tucking plunger.

11. The combination with means for forwarding cigars and envelops therefor having outstanding edges, of means for successively pinching together outstanding edges of the envelops over the cigars, mechanism for successively folding the leading edges over and tucking them behind the trailing edges, and a device for laying the folded and tucked edges flat on the cigars, said mechanism including coacting holding members, a folding plunger operating while said holding members are coacting, and a tucking plunger operating after said holding members have ceased to coact.

12. The combination with means for forwarding cigars and envelops therefor having outstanding edges, of means for successively pinching together outstanding edges of the envelops over the cigars, mechanism for successively folding the leading edges over and tucking them behind the trailing edges, and a device for laying the folded

and tucked edges flat on the cigars, said device including a stationary surface engaged by the folded and tucked edges in their forward travel.

In testimony whereof, I have signed my name to this specification.

FREDERICK CHAS. GLADECK.
